Application December 7, 1936, Serial No. 114,718
In Germany January 18, 1936

20 Claims. (CL 223—60)

This invention relates to an apparatus for treating and shaping hollow or tubular textile goods, and more particularly stockings, which, for the purpose of carrying out the treatment and shaping, are mounted on moving forms, the said treatment including essentially a pressing operation.

It is known to arrange pairs of pressing plates on either side of the track followed by the forms on which the articles to be pressed are mounted and to move the individual plates of each pair relative to one another and to the forms in such a manner that the articles mounted on the forms are subjected to a pressure treatment between the said plates. An essential condition for the satisfactory operation of a machine of this known kind is that the forms are moved intermittently. During the pressing operation between the pairs of plates the forms require to be stationary, whilst after the pressing plates have been lifted from the forms the latter are again advanced.

Since machines of this kind are normally combined with other treating apparatus, such as drying chambers and the like, it follows that the movement through the additional apparatus must also be intermittent, so that the overall length of the complete machine is comparatively large, and above all the output of the machine is small in relation to its size. These disadvantages are due solely to the intermittent movement of the forms.

Machines have also been proposed for the treatment of stockings mounted on forms, wherein the forms are moved continuously and the stockings mounted thereon are subjected to a pressure treatment between pairs of rollers. In this type of apparatus the disadvantages arising from an intermittent movement of the forms are avoided, but on the other hand there is a further disadvantage due to the nature of this type of apparatus.

It has been found in practice that the stockings or other articles whilst mounted on the forms require to be subjected to a pressure treatment for a certain length of time in order to accomplish the requisite shaping and pressing of the articles. In passing the forms having the articles mounted thereon between rollers, the time of treatment during which the articles are in contact with the rollers, that is to say, during which a pressure is exerted on the fabric, is obviously short.

It is the primary object of the present invention to provide means by which textile articles, such as stockings, mounted on forms may be subjected

to a pressing treatment, whilst at the same time the articles are maintained for a sufficient period in contact with the pressing elements.

A further object is to provide an apparatus of this kind which will not be unduly large as compared with the output obtained.

A still further object of the invention is to devise a form of apparatus in which will be united the advantages of the existing apparatus whilst avoiding the disadvantages thereof.

In the accomplishment of these and other objects and advantages which will become apparent as the description proceeds a method is employed which consists in mounting the articles under treatment on continuously moving forms and subjecting the articles thus mounted to a pressing treatment by means of pressing elements, such as pairs of plates, which for the actual pressing operation are moved together with the said forms through the machine.

In the preferred embodiment of this invention, the pressing plates are carried by two driving elements which each traverse the machine over endless tracks and are symmetrically arranged on opposite sides of the track followed by the forms.

When the pairs of pressing plates enter the form track the individual plates are conducted for a certain distance parallel to but spaced from the form with which they are to engage and the plates are then pressed against the form. This arrangement is particularly advantageous when the articles being treated are made of fine fabric such as artificial silk stockings, since it obviates any strain on, and deformation of, the fine artificial silk fabric of the stocking which may be set up even by the smallest movement on the part of the form in relation to the pressing plates.

Likewise the pressing plates when leaving the form track are first lifted evenly from the form and then guided for a certain distance parallel to the form before ultimately diverging for the return movement to the initial point of treatment. Preferably for this purpose the plates are furnished at their rear, taken in relation to the direction of movement, with abutments which extend beyond the pressing surface.

These abutments move in pairs on to a wedge provided at the outlet end of the apparatus and merge into a parallel guide which causes the parallel movement of the plates in spaced relation to the forms as above described.

The drive for the moving forms preferably is positively coupled with the drive for the plates. The plates are mounted on endless chains, the path of each of which consists of two lengths

running parallel to each other, the one nearer the forms being shorter than the other, so that the chain sections on the parts of the tracks connecting the two lengths are inclined outwardly away from the form track. This arrangement is obtained by the special disposal of the guide wheels and the fixed guides for the endless chains. It has the object of ensuring under all circumstances that after the lifting of the pressing plates from the forms there will be no further contact with the articles on the forms when the pressing plates are deflected from their straight run through the machine.

The pressing plates are so mounted as to be capable of a rocking movement in relation to their supporting chains and also so as to be capable of a reciprocatory movement across the chains. This arrangement has the advantage of causing each pressing plate to be so adjusted in relation to the form with which it is engaged that during the pressing operation it acts evenly on the article, for example, the stocking, at all points.

Preferably each pressing plate is mounted on its supporting chain mid-way of its width, for example, by means of a pin and slot connection, flat springs being provided which bear against the marginal zones of the plate for the purpose of holding the plate resiliently in a certain neutral position. It is, of course, also possible to employ other constructions for the same purpose.

The invention is illustrated by way of example in the accompanying drawings, in which:—

Figure 1 is an elevational view of one embodiment of the machine according to the invention.

Figure 2 is a plan view of the apparatus shown in Figure 1, partly in section.

Figure 3 illustrates on enlarged scale the method of mounting a pressing plate on its supporting chain.

Figure 4 illustrates on enlarged scale and somewhat diagrammatically the outlet end of the apparatus.

Figure 5 illustrates on enlarged scale the operation which takes place at the leading-in end of the apparatus.

Figure 6 illustrates a machine embodying a modified form of pressing plates.

Referring now to the drawings, there is provided on the base 1 of the apparatus a frame 2 composed of pillars and supports. In this frame there are arranged two gear wheels 3 and 4 which mesh with each other and are caused to rotate by a suitable drive (not shown). On the shafts of these gear wheels there are fixed sprocket wheels 5 and 6. The sprocket wheel 5 is connected by a driving chain 7 with a sprocket wheel 8, which is rigidly connected with a sprocket wheel 9, over which runs the chain 10 carrying the pressing plates. A similar arrangement is provided on the opposite side of the form track. Similar reference characters have been employed to denote like parts.

The sprocket wheels 9 are mounted on vertically disposed shafts 11. The forms, which in this embodiment are shown as upright, are mounted on the chain 12 in any suitable manner, and the form track comprising the said chain 12 and the forms 13 moves in the direction of the arrow P.

For the purpose of illustration the forms are shown to consist of flat solid metal. They may, however, also be hollow and, if desired, heated either directly or indirectly in any known manner.

On the chains 10, which are disposed symmetrically opposite to each other, there are lo-

cated the pressing plates 14. The particular method of mounting the pressing plates is illustrated by Figure 3. The pressing plate 14 is provided at its center with an abutment 15 having a slot 16. On the chain 10 there is situated a corresponding bearing member 17 having a pin 18 engaging in the slot 16. A flat spring 19, which is bent about the free end of the abutment 15 and two pins 20 in the bearing member, bears with its two free ends against the edges of the plate 14 for the purpose of holding the latter resiliently in a neutral or midposition. On either side of the form track there are situated guide faces 21, along which the chains 10 move.

At the leading-in end of the apparatus, as shown in Figure 5, there is also provided a special guide 22 which lies substantially parallel to but spaced from the guide face 21 at this point. The pressing plates 14 are provided at or near their leading edges with outstanding lugs 40 having upwardly standing pins 41 which, as the form is about to enter into its effective position, are engaged by the guide 22 to cause the pressing plate to swing round against the action of the spring 19 into a position in which it is parallel to the form track. Each presser plate travels for a short distance in this position parallel to the form track before it, as shown in the case of the presser plate on the right hand side of Figure 5, is pressed by its spring 19 against the form and accordingly against the article under treatment, for example, the stocking.

The endless chains 10 are so mounted (by means of the disposition of the gear wheels 9 and the guides 21) that the two parallel parts thereof are of unequal length, that part A (see Figures 2 and 5) which is disposed nearer the form track being shorter than the other part B and joining the same through an outwardly diverging part C. It will be apparent from Figure 5 that by reason of this arrangement the pressing plates are able to perform their turning movement at either end of the apparatus without entering into contact with the forms during this part of their movement.

The pressing plates are also provided at their upper ends with abutments 23. As shown in Figures 2 and 4, these abutments are situated at the rear of the pressing plates taken in relation to the direction of movement of the form track. At the outlet end of the machine there is provided a wedge member 24, which merges into a parallel guide 25. As the abutments 23 encounter the wedge member 24, the rear ends of the pressing plates are wedged apart, thereby maintaining the plates 14 in parallel relation to the forms 13. This arrangement has the advantage of causing the pressing plates 14 to be lifted from the forms and guided for a certain distance parallel to the forms before they diverge outwardly by reason of the inclined chain section C, as illustrated in Figure 4.

As shown in Figure 6 the pressing plates 14 may also be shaped in accordance with the forms, the foot portions 42, when the apparatus is to be used for treating stockings for example, then assuming a position within range of the preceding plate.

It will be understood that numerous embodiments of this invention are quite possible within the meaning of the above description and the annexed claims, so that the specific embodiments referred to in the above are intended merely to be illustrative and not in a limiting sense.

I claim:—

1. Apparatus for treating and shaping textile articles comprising a continuously moving con-

veyor, a plurality of shaping forms, each to receive a textile article to be treated and shaped, carried by said conveyor, two series of mutually co-operating presser plates arranged on opposite sides of said conveyor and normally spaced therefrom, means for moving said presser plates bodily to bring them into engagement with the forms and means for causing said presser plates whilst still in engagement with the article carried by the form to travel together with said form over a certain distance.

2. Apparatus for treating and shaping textile articles comprising a continuously moving conveyor, a plurality of shaping forms, each to receive a textile article to be treated and shaped, carried by said conveyor, two driving elements traversing endless paths of travel on opposite sides of said conveyor, means for driving said driving elements, two series of mutually co-operating presser plates carried individually by said driving elements, means for bringing said presser plates into engagement with the forms and means for causing said presser plates whilst still in engagement with the article carried by the form to travel together with said form over a certain distance.

3. Apparatus for treating and shaping textile articles comprising a continuously moving conveyor, a plurality of shaping forms, each to receive a textile article to be treated and shaped, carried by said conveyor, two driving elements traversing endless paths of travel on opposite sides of said conveyor, means for driving said driving elements, two series of mutually co-operating presser plates carried individually by said driving elements, means for bringing said plates individually into a position parallel to the conveyor as they approach same and for moving said presser plates parallel to but spaced from the forms for a certain distance, means for bringing said presser plates into engagement with the forms and means for causing said presser plates whilst still in engagement with the article carried by the form to travel together with said form over a certain distance.

4. Apparatus for treating and shaping textile articles comprising a continuously moving conveyor, a plurality of shaping forms, each to receive a textile article to be treated and shaped, carried by said conveyor, two driving elements traversing endless paths of travel on opposite sides of said conveyor, means for driving said driving elements, two series of mutually co-operating presser plates carried individually by said driving elements, means for bringing said presser plates into engagement with the forms, means for causing said presser plates whilst still in engagement with the article carried by the form to travel together with said form over a certain distance, means for removing said presser plates in a parallel manner away from said forms after they have travelled therewith through the machine and means for causing said presser plates thereafter to travel for a certain distance parallel to the form from which they have been disengaged.

5. Apparatus for treating and shaping textile articles comprising a continuously moving conveyor, a plurality of shaping forms, each to receive a textile article to be treated and shaped, carried by said conveyor, two driving elements traversing endless paths of travel on opposite sides of said conveyor, means for driving said driving elements, two series of mutually co-operating presser plates carried individually by said

driving elements, means for bringing said plates individually into a position parallel to the conveyor as they approach same and for moving said presser plates parallel to but spaced from the forms for a certain distance, means for bringing said presser plates into engagement with the forms, means for causing said presser plates whilst still in engagement with the article carried by the form to travel together with said form over a certain distance, means for removing said presser plates in a parallel manner away from said forms after they have travelled therewith through the machine and means for causing said presser plates thereafter to travel for a certain distance parallel to the form from which they have been disengaged.

6. Apparatus for treating and shaping textile articles comprising a continuously moving conveyor, a plurality of shaping forms, each to receive a textile article to be treated and shaped, carried by said conveyor, two driving elements traversing endless paths of travel on opposite sides of said conveyor, means for driving said driving elements, two series of mutually co-operating presser plates carried individually by said driving elements, means for bringing said presser plates into engagement with the forms, means for causing said presser plates whilst still in engagement with the article carried by the form to travel together with said form over a certain distance, outstanding abutments on the following edges of said presser plates, a wedge member engageable by said abutments after the presser plates on which they are carried have travelled with the form over the given distance and extension surfaces on said wedge member located parallel to the conveyor whereby the presser plates are first moved in a parallel manner away from the form with which they are engaged and are thereafter caused to travel for a certain distance parallel to the said form.

7. Apparatus for treating and shaping textile articles comprising a continuously moving conveyor, a plurality of shaping forms, each to receive a textile article to be treated and shaped, carried by said conveyor, two driving elements traversing endless paths of travel on opposite sides of said conveyor, means for driving said driving elements, two series of mutually co-operating presser plates carried individually by said driving elements, means for bringing said plates individually into a position parallel to the conveyor as they approach same and for moving said presser plates parallel to but spaced from the forms for a certain distance, means for bringing said presser plates into engagement with the forms, means for causing said presser plates whilst still in engagement with the article carried by the form to travel together with said form over a certain distance, outstanding abutments on the following edges of said presser plates, a wedge member engageable by said abutments after the presser plates on which they are carried have travelled with the form over the given distance and extension surfaces to said wedge member located parallel on the conveyor whereby the presser plates are first moved in a parallel manner away from the form with which they are engaged and are thereafter caused to travel for a certain distance parallel to the said form.

8. Apparatus for treating and shaping textile articles comprising a continuously moving conveyor, a plurality of shaping forms, each to receive a textile article to be treated and shaped, carried by said conveyor, two endless driving

chains adapted to move with said conveyor, two series of mutually co-operating presser plates carried by said driving chains, means for bringing said presser plates into engagement with the forms and means for causing said presser plates whilst still in engagement with the article carried by the form to travel together with said form over a certain distance.

9. Apparatus for treating and shaping textile articles comprising a continuously moving conveyor, a plurality of shaping forms, each to receive a textile article to be treated and shaped, carried by said conveyor, two endless driving chains adapted to move with said conveyor, two series of mutually co-operating presser plates carried by said driving chains, means for bringing said plates individually into a position parallel to the conveyor as they approach same and for moving said presser plates parallel to but spaced from the forms for a certain distance, means for bringing said presser plates into engagement with the forms and means for causing said presser plates whilst still in engagement with the article carried by the form to travel together with said form over a certain distance.

10. Apparatus for treating and shaping textile articles comprising a continuously moving conveyor, a plurality of shaping forms, each to receive a textile article to be treated and shaped, carried by said conveyor, two endless driving chains adapted to move with said conveyor, two series of mutually co-operating presser plates carried by said driving chains, means for bringing said presser plates into engagement with the forms, means for causing said presser plates whilst still in engagement with the article carried by the form to travel together with said form over a certain distance, means for removing said presser plates in a parallel manner away from said forms after they have travelled therewith through the machine and means for causing said presser plates thereafter to travel for a certain distance parallel to the form from which they have been disengaged.

11. Apparatus for treating and shaping textile articles comprising a continuously moving conveyor, a plurality of shaping forms, each to receive a textile article to be treated and shaped, carried by said conveyor, two endless driving chains adapted to move with said conveyor, two series of mutually co-operating presser plates carried by said driving chains, means for bringing said presser plates into engagement with the forms, means for causing said presser plates whilst still in engagement with the article carried by the form to travel together with said form over a certain distance, outstanding abutments on the following edges of said presser plates, a wedge member engageable by said abutments after the presser plates on which they are carried have travelled with the form over the given distance and extension surfaces on said wedge member located parallel to the conveyor whereby the presser plates are first moved in a parallel manner away from the form with which they are engaged and are thereafter caused to travel for a certain distance parallel to the said form.

12. Apparatus for treating and shaping textile articles comprising a continuously moving conveyor, a plurality of shaping forms, each to receive a textile article to be treated and shaped, carried by said conveyor, two endless driving chains adapted to move with said conveyor, the path of said chains including two parts of differ-

ent lengths, the shorter of which is disposed nearer the conveyor, and two inclined parts, two series of mutually co-operating presser plates carried by said driving chains, means for bringing said presser plates into engagement with the forms and means for causing said presser plates whilst still in engagement with the article carried by the form to travel together with said form over a certain distance.

13. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, means for mounting the individual presser plates of said pairs each on one of said driving chains, means for allowing said presser plates to rock with respect to said chains, means for allowing reciprocatory movement of said presser plates transversely to the length of the chains on which they are mounted, means for bringing said presser plates into engagement with the forms and means for causing said presser plates whilst still in engagement with the article carried by the form to travel together with said form over a certain distance.

14. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, means for mounting the individual presser plates of said pairs each on one of said driving chains, means for allowing said presser plates to rock with respect to said chains, means for allowing reciprocatory movement of said presser plates transversely to the length of the chains on which they are mounted, means for bringing said plates individually into a position parallel to the conveyor as they approach same and for moving said presser plates parallel to but spaced from the forms for a certain distance, means for bringing said presser plates into engagement with the forms and means for causing said presser plates whilst still in engagement with the article carried by the form to travel together with said form over a certain distance.

15. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, means for mounting the individual presser plates of said pairs each on one of said driving chains, means for allowing said presser plates to rock with respect to said chains, means for allowing reciprocatory movement of said presser plates transversely to the length of the chains on which they are mounted, means for bringing said presser plates into engagement with the forms, means for causing said presser plates whilst still in engagement with the article carried by the form to travel together with said form over a certain distance, means for removing said presser plates in a parallel manner away from said forms after they have travelled therewith through the machine and means for causing said presser plates thereafter to travel for a certain distance parallel to the form from which they have been disengaged.

to travel for a certain distance parallel to the form from which they have been disengaged.

16. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, a lug disposed on each plate intermediate the edges of the same, a pin-and-slot connection between each of said lugs and said driving chains, flat blade springs controlling said pin-and-slot connections and engaging at their free ends with the marginal zones of said plates, means for bringing said presser plates into engagement with the forms and means for causing said presser plates whilst still in engagement with the article carried by the form to travel together with said form over a certain distance.

17. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, a lug disposed on each plate intermediate the edges of the same, a pin-and-slot connection between each of said lugs and said driving chains, flat blade springs controlling said pin-and-slot connections and engaging at their free ends with the marginal zones of said plates, means for bringing said plates individually into a position parallel to the conveyor as they approach same and for moving said presser plates parallel to but spaced from the forms for a certain distance, means for bringing said presser plates into engagement with the forms and means for causing said presser plates whilst still in engagement with the article carried by the form to travel together with said form over a certain distance.

18. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, a lug disposed on each plate intermediate the edges of the same, a pin-and-slot connection between each of said lugs and said driving chains, flat blade springs controlling said pin-and-slot connections and engaging at

their free ends with the marginal zones of said plates, means for bringing said presser plates into engagement with the forms, means for causing said presser plates whilst still in engagement with the article carried by the form to travel together with said form over a certain distance, means for removing said presser plates in a parallel manner away from said forms after they have travelled therewith through the machine and means for causing said presser plates thereafter to travel for a certain distance parallel to the form from which they have been disengaged.

19. Apparatus for treating and shaping textile articles comprising a continuously moving conveyor, a plurality of shaping forms, each to receive a textile article to be treated and shaped, carried by said conveyor, two endless driving chains adapted to move with said conveyor, a plurality of pairs of presser plates each co-operating with a form, a lug disposed on each plate intermediate the edges of the same, a pin-and-slot connection between each of said lugs and said driving chains, flat blade springs controlling said pin-and-slot connections and engaging at their free ends with the marginal zones of said plates, means for bringing said presser plates into engagement with the forms, means for causing said presser plates whilst still in engagement with the article carried by the form to travel together with said form over a certain distance, outstanding abutments on the following edges of said presser plates, a wedge member engageable by said abutments after the presser plates on which they are carried have travelled with the form over the given distance and extension surfaces on said wedge member located parallel to the conveyor whereby the presser plates are first moved in a parallel manner away from the form with which they are engaged and are thereafter caused to travel for a certain distance parallel to the said form.

20. Apparatus for treating and shaping articles consisting in the combination of an endless conveyor arranged to travel in a predetermined path, shaping forms carried by said conveyor, pressing elements for simultaneously engaging opposite sides of said forms in pressing relation, means to cause said elements to assume said pressing relation at one place in the travel of said forms, means to move said elements with said forms while maintaining said pressing relation, and means to release said pressing relation at a different place in the travel of said forms.

FRITZ SCHUSTER. 55
